UNITED STATES PATENT OFFICE.

SIDNEY A. REEVE, OF TOMPKINSVILLE, NEW YORK.
INTERNAL-COMBUSTION ENGINE.

1,253,528.

Specification of Letters Patent. Patented Jan. 15, 1918.

Application filed April 15, 1914. Serial No. 332,034.

To all whom it may concern:

Be it known that I, SIDNEY A. REEVE, a citizen of the United States, residing at Tompkinsville, in the county of Richmond and State of New York, have invented a new and useful Improvement in Internal-Combustion Engines, of which the following is a specification.

My invention relates to engines having two or more cylinders operating upon the Beau de Rochas or other so-called "four-stroke" cycles, in which the back-strokes of the piston are used alternately for exhausting the burnt charge and compressing the next charge. Its object is to improve the efficiency and power by perfecting the scavenging of the burnt gases from the cylinder, increasing the expansion and freeing the exhaust. It also gives the designer of the engine a greater latitude in choice of degree of compression to be employed.

Referring to the drawings, in which corresponding parts are designated by corresponding marks of reference,—

Figure 1 is a partial section on the plane of the crank-shaft and cylinder-axes of two cylinders of such an engine in which the two cylinders illustrated are arranged side by side in that plane, their pistons working in substantial unison upon a single crank.

Fig. 2 is a partial section on a plane normal to the crank-shaft and containing the axis of the left-hand cylinder of Fig. 1, viewed from the left.

Fig. 3 is a partial section through the plane of the axes of a similar pair of cylinders, but showing a modification of my invention from the form shown in Figs. 1 and 2.

Fig. 4 is a diagram of shaft, crank-pin and eccentric centers of a ten-cylinder engine having its cylinders arranged radially about the shaft in five pairs, each pair similar to Figs. 1 and 2.

Fig. 5 is a similar diagram of shaft, crank-pin and eccentric centers of a nine-cylinder engine having its cylinders arranged each in a different plane radiating from, and coinciding with, the axis of, the crank-shaft.

Fig. 6 is a longitudinal vertical section of the eccentric element (with crank-shaft in elevation) of the engine of Fig. 5.

Fig. 7 is a vertical section along the plane YY of Fig. 6, looking toward the left, the

eccentric above the plane of the paper being shown by broken line.

Fig. 8 is a diagram of the geometric development of the outer ends of the cylinders of Fig. 5 into a plane, as if the paper had been wrapped about the outer ends of the cylinders in a periphery centering in the crank-shaft axis, with the axis 55 55 of Fig. 8 parallel with and vertically above the shaft axis, as at I of Fig. 5.

In the drawings 1 is a cylinder-body comprising cylinders for the two pistons 2, 2; 3 is the crank-shaft; 4 is the crank and 5 the crank-pin driven in common by the pair of cylinders shown. The two sets of cylinders and pistons will be referred to in general as A and B respectively, as marked. In the drawings cylinder A is shown at the end of its exhaust-stroke and cylinder B at the end of its compression-stroke.

Each piston 2 has a wrist-pin 7 and a connecting-rod 6. Between the connecting-rods 6, 6 (Figs. 1 and 2) and the crank-pin 5 is a piece 10—11—12—13—14—15—16 (hereinafter referred to as the rock-sleeve) which, although it may be subdivided for purposes of construction, is virtually one solid piece. It comprises a concentric sleeve 13 on the crank-pin 5, eccentrics 11 and 12, arms 15 and 16, and pin 14. The two eccentrics are the equivalent of two short cranks having radii bearing a mutual angular relation, in Figs. 1 and 2, of preferably less than 180° and more than 90°, but these limits may be disregarded without departing from the spirit of my invention. The two arms 15 16 have radii approximately bisecting the angle between the radii of the eccentrics. The two arms act as one, and are made duplicate only for convenience. To the extremities of the pin 14 in these arms are attached the tension-springs 17 and 18, the other ends of which are attached to the pins 19 and 19^a fixed in the rods 6, 6. Except for the elastic action of the springs 17 and 18, which may not always be present, the rock-sleeve rotates freely on the crank-pin, without constraint into any definite position.

In the modification shown in Fig. 3 the crank-shaft and crank are not shown, but are understood as driven by the connecting-rods 26, 26 working upon a single crank. 20 is a cross-head, suitably guided by slides not shown, driving the connecting-rods by the pin 27. The left-hand face of this cross-

head comprises a plane surface, and against this surface bears a rocker 21 in which are fixed pins 22, 22 and 29, supposedly protruding upon the far side also. The pins 22
 5 are connected with the two pistons respectively by the links 23, 23. The cross-head bears a pin 28 which is connected by the tension-spring 36 with the pin 29. The rocker 21 is guided by the links 24, 24,
 10 swinging on pins 25, 25 fixed in the cross-head (with the requisite lost motion or elasticity properly provided) so that each link 28 will coincide approximately with the axis of its cylinder when its end of the rocker
 15 is in contact with the cross-head.

The engine-cylinders are supposed to be equipped with the usual valves, valve-gear, frames, etc., for "four-stroke cycle" action, with either constant-volume or constant-
 20 pressure combustion, or both. The cylinders of Figs. 1 and 2 are also shown equipped each with a supplementary annular exhaust-port 30, leading to exhaust-corridor 31 and exhaust-pipe 32. The same construction
 25 might be used in Fig. 3.

In operation, the action of the rock-sleeve of Figs. 1 and 2 (or equivalent rocker in Fig. 3) occurs chiefly during the back-stroke of the two pistons. At the beginning of
 30 the back-stroke the pressures in the two cylinders are equal, the forces at work upon the two eccentrics 11 and 12 are equal, and the tension of the two springs 17, 18 will have drawn the arms 15, 16 into approximate
 35 coincidence with the plane of Fig. 1, from which plane the two eccentrics will tend to bear equal departures. But as the back-stroke progresses the action of the valves imprisons the gases within cylinder
 40 B, while leaving open the exhaust for those of cylinder A; wherefore the pressure rises rapidly in B. This unbalances the forces at work upon the rock-sleeve and tilts it gradually toward the position shown.
 45 This position will be assumed more or less accurately, according to the influence of the inertia of the various moving parts, before the compression-stroke is completed; but since the springs 17, 18 shown in Figs. 1
 50 and 2 gain in mechanical advantage as the rock-sleeve assumes angularity, whereas the fluid forces upon piston B lose it, the parts will never quite reach the position shown (except as a possible result of inertia). If
 55 the springs 17, 18 were absent from the structures of Figs. 1, 2 and 3, as in the structures of Figs. 4 and 5 which have no springs, the positions shown in the drawings will still be assumed perfectly, as the
 60 result of fluid forces alone, acting upon the pistons. As a result of this rotation of the rock-sleeve and eccentrics, piston B fails to reach the end of its cylinder by the clearance shown, which is that suitable for the
 65 desired degree of compression, while piston

A is driven quite home (barring an inevitable minimum of clearance), whereby the exhaust-gases are driven completely from cylinder A.

It is to be understood that the springs of 70 Figs. 1 and 2, when the eccentrics 11, 12 bear a relative angle appreciably less than 180°, are superfluous to the normal operation of the engine, since the fluid forces at work upon the pistons suffice to enforce all 75 the requisite movements of the eccentrics; but when the engine has been at rest for a time eccentrics relatively so located might have become rotated by accident (in the absence of the springs) into the position 80 where eccentric 11 was vertically above the crank-pin, whereupon the starting of the engine would develop a destructive collision before the usual fluid forces could assume control. If the relative angle of eccentrics 85 in Figs. 1 and 2 be substantially 180° the springs are plainly necessary for normal operation, to throw the upper eccentric off center after the completion of the suction-stroke.

But where the eccentric angles and radii are such, in a two-cylinder engine like Fig. 1, or where the number or relative position of cylinders is such, as in Figs. 4 and 5, that there is no danger of the eccentric of the 95 compressing piston being caught on upper center, or of being improperly near the cylinder, so as to develop collision, springs are not necessary. Springs such as 17, 18 are therefore a part of my invention only as a 100 well known means for accomplishing what may preferably be accomplished by the fluid forces acting upon the pistons, or by other means. Besides the fluid forces there are inertia-forces at work upon the pistons and 105 eccentrics. In Figs. 1 and 2, as the pistons approach the upper end of their stroke, not only will the eccentric piston B be pressed downwardly by the compression-pressure but that of piston A may be forced upwardly by inertia-forces. This would tend to rotate the sleeve beyond the dead-center position for piston B, were not the explosion-pressure thereon so heavy as to prevent. In such case centrifugal force or 110 inertia, acting upon eccentric A, may become the true motive force to be relied upon to actuate said eccentric, in domination over the fluid forces. Thus in high-speed engines the inertia-forces may become the controlling forces both in design and operation, in 115 my invention as in any other feature of a high-speed engine.

As combustion and expansion ensue the heavy fluid forces at work upon piston B 120 can have no appreciable effect upon the angularity of the rock-sleeve, because it is already virtually upon dead-center. The two pistons retain substantially the relative position shown until the opening of 130

exhaust equalizes or reverses the pressures in the two cylinders. Owing to this fact the working piston will travel farther down its cylinder than the idle one, thus uncovering the annular exhaust-port 30, which the idle piston fails to reach. This provides a more free exhaust and a greater degree of expansion than is ordinarily attainable in four-stroke cycle engines.

and 2, metallic springs or some other displacing device are obviously needed for drifting purposes if the eccentric-angle be less than 180° , or for normal operation if this angle be 180° ; but where two or more such pairs are associated piston-action may be relied upon for displacing the eccentrics from dead center or for otherwise limiting properly its motion. The exact character of such means is not a feature of this invention, 75 so long as it operates without shock.

In engines having a sufficient number of cylinders located radially around the crank-shaft the device of Figs. 1 and 2 is applicable by leaving the rock-sleeve free to rotate 80 completely around the crank-pin under control by piston-forces only. The recurrent cycles in the successive cylinders will cause the sleeve to rotate, but irregularly. In such an engine the cylinders may be arranged in pairs like Fig. 1 or they may all be in the same plane, or they may combine these two plans. The only requisite is that combustion shall occur in adjacent cylinders 85 at each alternate revolution, as is usual in four-stroke cycle engines. Fixing the crank-shaft and making the cylinders the rotor has no bearing upon the applicability of my invention, although reversing some of the descriptive terms used.

Figs. 4 and 5 are diagrams of crank positions, and sleeve or eccentric positions, arranged to show how my invention may be applied to engines of different arrangements of multiple cylinders.

Fig. 4 illustrates diagrammatically an engine of ten cylinders upon a single crank, arranged radially about the crank-shaft in five pairs, each pair parallel as in Fig. 1.

The five "A" cylinders of these five pairs 105 drive upon a single eccentric common to the five, upon the crank-pin, while the five "B" cylinders drive upon another single eccentric common to the five, the two eccentrics being 110 solidly connected upon a common sleeve, as in Fig. 1.

Each of the five broken-and-dotted lines radiating from the center of Fig. 4 represents the plane of a section similar to Fig. 1, the pitmen of the five "A" cylinders being 115 journaled upon the eccentric 11 or upon the head of the left-hand pitman 6 in any suitable manner, as is now commonly done, and the pitmen of the five "B" cylinders being 120 similarly journaled upon the eccentric 12 or upon the corresponding pitman 6.

Fig. 5 illustrates diagrammatically an engine of nine cylinders upon a single crank, arranged radially about the crank-shaft at 125 nine equal angles, all the cylinders being either substantially in the same plane transverse to the shaft, or, if in three different planes, so distributed only for convenience of alinement with their respective eccentrics.

The sleeve on the crank-pin in this case carries three eccentrics similar to 11, 12 of Figs. 1 and 2, the centers of which are marked x , y and z respectively, bearing a mutual angular relationship of 120° . The nine cylinder-axes are in three different planes transverse to the crank-shaft, cylinders I, IV and VII being in the plane of eccentric x , cylinders II, V and VIII in the plane of eccentric y , and cylinders III, VI and IX in the plane of eccentric z . Each of these three sets of three cylinders drives the crank-pin through connecting-rods bearing upon the single eccentric respectively common to the three cylinders and lying in their plane.

In Figs. 6 and 7 the three eccentric-centers x , y and z are those respectively of eccentrics 111, 211 and 311, the three eccentrics lying in the planes X, Y and Z respectively and being structurally solidified into a unit rotating freely about the crank-pin axis 50, which in turn rotates about the shaft-axis 0.

In Fig. 4 the solid circle represents the path of the crank-pin and the two concentric dotted circles the extremes of piston-adjustment away from its mean position, in either direction, requisite for the functions of per- feet scavenging, extended expansion, over- running of exhaust-port or clearance for suitable compression, as already described. The double small circles represent various positions of the center of the crank-pin or sleeve, and the little adjacent single circles represent the centers of the two eccentrics, which are in this case separated by an angle of 180° and of a throw equal to the distance between solid and dotted large circles. The two sets of five cylinders each, with the directions of their center-lines, are indicated by radii marked with the Roman numerals: I, II, III, IV, V, vi, vii, viii, ix and x, the capital letters referring to the cylinders in one plane attached to one eccentric and the lower-case letters referring to those in the other plane attached to the other eccentric. The valve-gear is supposedly arranged to develop combustion in the ten cylinders in their numerical order.

Starting first with cylinder I, the development of compression and explosion in this cylinder will force its eccentric and piston into the position B, Fig. 1, while the piston of cylinder VI is forced into the position A (except that its eccentric is then directly above the crank-pin center, instead of obliquely as in Fig. 1). Throughout the arc of crank-motion I-II cylinder I will be chiefly in control of the angular position of the rock-sleeve; but as radius II is approached the fluid force of cylinder I is dying out rapidly, while that of cylinder II is increasing rapidly, whereby as combustion occurs in cylinder II that piston supersedes

cylinder I in control, forcing the two eccentrics approximately into alinement with radius II without shock. Continuing thus around the circle to radius V, each cylinder of this set assumes control of the rock-sleeve in turn, without shock, the rock-sleeve rotating with an average angular speed equal to that of the crank.

But when cylinder V has burnt and slightly expanded its charge a new state of equilibrium is reached, as indicated. When the crank is about midway between radii V and vi, while the fluid forces of cylinder V are still forcing its eccentric powerfully in the direction of the arrow Y, the compression-forces of cylinder vi develop rapidly a force upon the other eccentric in the direction of the arrow y ; for in the position drawn the clearance of cylinder vi has already been reduced almost to the minimum suitable for combustion. Therefore between about the position drawn and the position vi the rock-sleeve is rotated quickly and powerfully, but in stable equilibrium and without shock, in the opposite direction from that of the engine, bringing the eccentric of the second set of cylinders into the position of that occupied before by that of the first set. Thus during each revolution the eccentric of one working set of cylinders is held nearest to the crank-shaft, while that of the idle set of cylinders is farthest from it, thus accomplishing for all the cylinders the operation described for Fig. 1.

In Fig. 5, as in Fig. 4, the axes of the nine cylinders are indicated by Roman numerals. But in this case the valve-gear is arranged to develop combustion in the several cylinders in the following order: I, III, V, VII, IX, II, IV, VI, VIII, I, etc. Starting with the crank-pin in position I, the operation is as follows: The heavy working-pressure in cylinder I forces eccentric x to its lower dead-center, as drawn. As the crank-pin passes position II this cylinder (its piston attached to eccentric y) is idle at the end of its exhaust-stroke. The position of eccentric y at this time shows how the perfect exhaust described in relation to Fig. 1 is performed in cylinder II of Fig. 5. As the crank-pin approaches position III the angularity of connecting-rod I brings the rock-sleeve into approximation to the position drawn at III; but in addition, the fluid forces of cylinder I are dying out rapidly, while the compressive resistance of cylinder III, acting upon eccentric z , is rapidly increasing. Therefore near position III the control of the rock-sleeve passes gradually and without shock from cylinder I to cylinder III.

The phenomena just described then repeat themselves in the arc III-V of the crank-circle, but with eccentric z playing the part formerly performed by eccentric x , etc.; and

in crank-arc V—VII the performance is repeated with eccentric y in the leading rôle. Thus, as the engine rotates the rock-sleeve also rotates virtually continuously, but in the opposite direction and at an average speed a little greater than that of the engine. In this case not only is the elastic control of the rock-sleeve no longer needed to overcome inertia, but the smoothness of operation may be enhanced by expanding the rock-sleeve into a little fly-wheel, the inertia of which will steady its otherwise somewhat irregular angular motion.

With the particular number of cylinders illustrated in Fig. 5 the extra length of exhaust-stroke described in relation to Fig. 1 does not appear, the exhaust and suction strokes carrying the piston out to about the same extreme position; but with twelve cylinders, for instance, arranged as in Fig. 5, working upon a rock-sleeve of three eccentrics (eccentric x carrying cylinders I, IV, VII and X, eccentric y cylinders II, V, VIII and XI, and eccentric z cylinders III, VI, IX and XII) this feature of advantage reappears. This extension of the working-stroke beyond the end of the suction-stroke both permits a free annular exhaust and also increases the degree of expansion.

Various other methods of adapting my invention to the many different arrangements of cylinders common in internal combustion engines will occur to the designer of each type, without the possibility of illustrating them all here. Thus a four-cylinder single crank V-type engine, with the four eccentrics located relatively at 90° , would operate as Fig. 1 does, except that the period during which re-adjustment of eccentrics was accomplished would occupy 180° of crank motion, instead of 72° as in Fig. 4, and so the engine would be smoother in operation. Such a single crank engine would be unbalanced; but an eight-cylinder two-crank V-type engine with cranks located at 180° , would operate in the same way and in perfect balance.

It will be noticed that in all of the structures described above, the opposing forces set up in the sleeve-and-eccentrics or rocker device by the pistons, together with any additional force introduced to throw an eccentric off center, act always in stable equilibrium. That is to say, the resultant of all such forces in combination acts to rotate the rocker into a new position in such a way that the moment, or effectiveness, of this resultant dies out gradually, without shock, as motion progresses under its influence, until a final position is reached in which said moment has become zero. Also, for any given assortment of forces in the pistons there is always a single definite position of rocker corresponding thereto.

This is the essence of stability of equi-

librium. It is also the essence of my invention. I am aware that other suggestions have been made for devices displacing the pistons of internal-combustion engines relatively by the action of piston-forces; but they have been either such as to act always in unstable equilibrium—the moment or effectiveness of the forces increasing as motion progresses, until shock alone arrests said motion—or they have been such as to act much of the time in neutral or indifferent equilibrium, there being no definite position of the rocker for any given assortment of forces on the pistons; or else, when stable equilibrium happens to be present momentarily, in the form of a dead center, no means is shown for throwing the rocker off center after its duty has been performed.

It is further to be understood that my invention consists in a merely relative arrangement of cylinder-axes and eccentric-radii such as will develop this stability of equilibrium. That is to say, whether the cylinder-axes be kept parallel, as in Figs. 1 and 2, while the eccentrics are set at odd angles, or whether it be the cylinder-axes which are set at odd angles, as in Figs. 4 and 5, makes no difference. Nor again, whether, in Figs. 4 and 5, it be the mate of a parallel pair of cylinders which functions to throw the rock-sleeve out of center with the working-cylinder, after its working-stroke is finished, or some cylinder oblique thereto, also makes no difference. It is mere congregation of cylinders combined with obliquity between cylinder-axis and eccentric-radius, so as to produce stability of equilibrium in the rock-sleeve, which constitutes the essence of my invention.

It is plain from the above that my invention may be embodied in many different relative arrangements of cylinder-axis and eccentric, and I therefore do not confine myself to those illustrated.

Having thus described my invention what I claim and desire to secure by Letters Patent is,—

1. In an engine of the type described, the combination of a plurality of pistons and cylinders, a crank-pin common to the pistons, and unconstrained means located between said pistons and crank-pin for displacing the pistons relatively to the crank-pin in different directions, said means being actuated by the forces on the pistons and so formed that said forces always combine therein in stable equilibrium, substantially as described.

2. In an engine of the type described, the combination of a plurality of cylinders and pistons, a crank-pin common to the pistons, and unconstrained means actuated by the forces on the pistons located between said pistons and crank-pin for displacing the pistons relatively to the crank-pin in different

directions and so formed as to assume gradually a dead-center position relatively to each piston as said piston in turn becomes subject to major fluid force, substantially as described.

3. In an engine of the type described, the combination of a plurality of cylinders and pistons, a crank-pin common to the pistons, a pitman for each piston, an unconstrained sleeve rotating upon said crank-pin, a plurality of eccentrics fixed on said sleeve, each eccentric forming a pitman journal for a piston, the eccentrics and piston-axes arranged in such angular relation that the 10 sleeve is rotated by the forces on the pistons always in stable equilibrium, substantially as described.

4. In an engine of the type described, the combination of a plurality of cylinders, pistons and pitmen, a crank-pin common to all, a sleeve rotating unconstrainedly upon said crank-pin and eccentrics fixed upon said sleeve and forming journals for the pitmen, the angular relation between cylinder-axes 20 and eccentric-radii being such that whenever major force upon one pitman has driven its rock-sleeve eccentric into a dead-center position relatively to that piston a piston engaged in compression is out of dead-center 25 position relatively to its eccentric, substantially as described.

5. In an engine of the type described, two sets of parts, each set comprising a cylinder, piston and pitman or a plurality of such, arranged for alternate combustion between the 30 two sets, a crank-pin common to the two sets, a sleeve rotating unconstrainedly on said pin, eccentrics forming pitman-journals fixed on said sleeve, the eccentrics bearing such angular relation to their respective cylinder-axes that the sleeve is rotated on the pin by the piston-forces always in stable equilibrium, substantially as described.

6. In an engine of the type described, the combination of a plurality of cylinders and pistons arranged for combustion in succession, a crank-pin common to said cylinders, and unconstrained means between said pistons and the crank-pin actuated by the piston-forces for displacing the pistons relatively to the crank-pin, said means being arranged to come gradually into dead-center position relatively to each piston which in turn undergoes compression and combustion, 45 while being at the same time off dead center relatively to the next piston to undergo compression and combustion, substantially as described.

7. In an engine of the type described, two

sets of parts, each set comprising a cylinder 60 and a piston or a plurality of such, arranged for alternate combustion between the two sets, a crank-pin common to the two sets, an annular exhaust-port in each cylinder at the extreme point toward the crank-pin overrun by the piston, and unconstrained means located between piston and crank-pin and actuated by the piston-forces for displacing away from the crank-pin the piston momentarily subject to minor force by permitting 70 the piston momentarily subject to major force to approach gradually the crank-pin, toward a dead-center position of said means, said means being always in stable equilibrium, substantially as described. 75

8. In a four-cycle engine having a plurality of cylinders burning their charges at different times, and having a common crank-pin, an unconstrained member transmitting forces from the several pistons to the common crank-pin so formed as to assume substantially a dead-center position relative to the piston-force momentarily superior to the others, and means for displacing said member from said dead-center position after said piston-force has lost its superiority, substantially as described. 80

9. In a four-cycle engine having a plurality of cylinders burning their charges at different times, and having a common crank-pin, an unconstrained member transmitting the forces from the several pistons to the common crank-pin so formed as to assume gradually a stable position relatively to each piston working in turn, with means for displacing said member from said position gradually and stably when said piston has ceased working, substantially as described. 90

10. In an engine of the type described, the combination with a plurality of cylinders 100 and pistons, of a crank pin common to the pistons, a pitman for each piston, and an eccentric member rotating unconstrainedly on said crank pin and forming a journal for the said plurality of pitmen, the piston axes 105 being arranged in such angular relation to the eccentric-radii that the eccentric member is rotated by forces on the pistons always in stable equilibrium, substantially as described. 110
